UNITED STATES PATENT OFFICE.

FRANK REDDAWAY, OF PENDLETON, COUNTY OF LANCASTER, ENGLAND.

WOVEN BELTING.

SPECIFICATION forming part of Letters Patent No. 334,895, dated January 26, 1886.

Application filed April 16, 1885. Serial No. 163,512. (Model.) Patented in England January 10, 1884, No. 1,110.

To all whom it may concern:

Be it known that I, FRANK REDDAWAY, a subject of the Queen of Great Britain and Ireland, and residing at Pendleton, county of 5 Lancaster, England, belting - manufacturer, have invented an Improved Woven Belting, (for which I have obtained a patent in Great Britain, No. 1,110, January 10, 1884,) of which the following is a specification.

10 My invention consists of certain improvements in the construction of woven belting, such as is used in place of leather belting for transmitting rotary motion. Such belting is usually made of cotton, canvas, or sail-cloth. 15 In some cases the belt has been woven complete, so as not to require folding, cotton yarn being used; but the objection to this is its liability to stretch and its limited strength. In order, therefore, to obtain greater strength 20 and less tendency to stretch, I substitute camel-hair yarn in place of a portion of cotton yarn.

The figure in the accompanying drawing is a perspective view of a portion of a belt embodying my invention, *a* representing the cotton warps, *b* the camel-hair warps, and *d* the weft-threads.

In the making of a belt of average strength I preferably use a proportion of, say, four cotton warps and four camel - hair warps, in addition to two binding-warps, with wefts also 30 of camel-hair. This furnishes a belt containing about two-thirds camel-hair and one-third of cotton, and gives good results; but I may increase or decrease the proportion of camel-hair, as found to be desirable.

35 I claim as my invention—

1. A woven belting composed of cotton and camel-hair in suitable proportions, substantially as described.
2. A woven belting having two sets of 40 warps, one of cotton and the other of camel-hair, together with camel-hair wefts, substantially as set forth.

In testimony whereof I have signed my name to this specification in the presence of two sub- 45 scribing witnesses.

FRANK REDDAWAY.
